UNITED STATES PATENT OFFICE.

JOHN HEDIN, OF MARIESTAD, SWEDEN, ASSIGNOR TO AKTIEBOLAGET REDUKTOR, MARIESTAD, SWEDEN.

ARRANGEMENT FOR INCREASING THE LIFE OF RIFLED SHOOTING WEAPONS.

No Drawing.

Application filed October 21, 1924. Serial No. 745,002.

To all whom it may concern:

Be it known that I, JOHN HEDIN, a subject of the King of Sweden, residing at Mariestad, Sweden, have invented certain new and useful Improvements in Arrangements for Increasing the Life of Rifled Shooting Weapons, of which the following is a specification.

The precision of aim in shooting with rifled weapons of certain kinds, particularly hand-fire-arms, is to a great extent dependent on the accuracy of the barrel and of the rifles, especially in the portion of the barrel situated adjacent the mouth, or in the edge 15 of the bore proper at the mouth. In the same degree as the walls of the bore or the rifles are worn at or near the mouth—whereby also the edge of the bore at the mouth may be influenced—the certainty of aim is 20 reduced.

Thus the life of the weapon or of the barrel will to a great extent depend on how much the bore adjacent the mouth and the edge forming the transition between the bore 25 and the plane of the mouth is worn or injured by shooting or, otherwise, by careless treatment in cleaning, or by blows and shocks. Besides, it should be observed that the wear may be both of a mechanical and 30 a chemical nature, depending substantially on the character of the projectile and of the powder gas.

The present invention relates to arrange-

ments having for their purpose to increase the life of the weapon, or to maintain the 35 certainty of its aim, and the invention is principally characterized by the rifled wall of the bore adjacent the mouth, especially the edge of the mouth—the transition edge between the bore and the plane of the 40 mouth—being tempered to a greater or smaller depth.

The object in view may also be attained by making the rifled wall of the bore adjacent the mouth of a material which is capable to better withstand wear than the other portions of the rifled wall, and which material may be connected therewith in any suitable manner.

What I claim as new and desire to secure 50 by Letters Patent of the United States of America is:

An arrangement for increasing the life of rifled weapons, particularly of hand-fire-arms, characterized by the rifled wall of the 55 bore at the mouth, especially the edge of the mouth, being tempered to a greater or smaller depth, while the remaining portions of the rifled wall of the bore are untempered.

In testimony whereof I affix my signature 60 in presence of two witnesses.

JOHN HEDIN.

Witnesses:

GUMMAR CROSSLIN,
L. BERG VON SUIDE.
